(57) **CLAIM**

The ornamental design for a cot fastener as shown and described.

DESCRIPTION

FIG. 1 is a perspective view of a cot fastener; FIG. 2 is a front elevation view thereof; FIG. 3 is a left side elevation view thereof; FIG. 4 is a rear elevation view thereof; FIG. 5 is a right side elevation view thereof; FIG. 6 is a top plan view thereof; and, FIG. 7 is a bottom plan view thereof.

The broken lines, the areas within them, and the unshaded areas bounded by broken lines and solid lines depict portions of the cot fastener that form no part of the claimed design.

1 Claim, 4 Drawing Sheets

Related U.S. Application Data

a continuation of application No. 29/668,739, filed on Nov. 1, 2018, now Pat. No. Des. 875,950, which is a continuation of application No. 16/025,526, filed on Jul. 2, 2018, now Pat. No. 11,090,207, and a continuation of application No. 29/613,059, filed on Aug. 7, 2017, now Pat. No. Des. 833,623, said application No. 16/025,526 is a continuation of application No. 15/290,004, filed on Oct. 11, 2016, now Pat. No. 10,058,464, said application No. 29/613,059 is a continuation of application No. 29/536,593, filed on Aug. 18, 2015, now Pat. No. Des. 794,205.
